UNITED STATES PATENT OFFICE.

FRED FIELDING AND THOMAS POTTER, JR., OF OLDHAM, ENGLAND.

ANTIBALLOONING AND THE LIKE DEVICE FOR RING-SPINNING AND DOUBLING FRAMES.

1,391,883.

Specification of Letters Patent. Patented Sept. 27, 1921.

Application filed June 29, 1920. Serial No. 392,792.

(GRANTED UNDER THE PROVISIONS OF THE ACT OF MARCH 3, 1921, 41 STAT. L., 1313.)

To all whom it may concern:

Be it known that we, FRED FIELDING and THOMAS POTTER, Jr., both British subjects residing at Oldham, in the county of Lancaster, England, have invented certain new and useful Improvement in Antiballooning and the like Devices for Ring-Spinning and Doubling Frames, (for which we have filed application in Great Britain Feb. 14, 1919, 10 Patent No. 138,432,) of which the following is a specification.

This invention relates to that type of anti-ballooning and like devices for ring spinning and doubling frames which comprise chiefly an annular member located concentrically a short distance above the ring and means for securing said member to the ring rail.

This invention has for its object to simplify and so form and apply said annular anti-ballooning member that the ends will be more efficiently controlled, remain better separated and be kept cleaner than hitherto has been the case and the device will also serve as a dirt catcher. Said annular anti-ballooning member according to this invention is located in very close proximity to the traveler ring and is rim shaped and has at the back a rearwardly extending band or arm adapted to be secured to a support serving also as a dirt catcher usually employed between each two rings or similarly shaped means projecting vertically from the ring rail.

We attain this object by the means illustrated in the accompanying drawing, in which—

Figure 1, is a cross section and Fig. 2, a plan of a ring rail fitted with anti-ballooning members constructed and applied to the ring rail in accordance with this invention.

Similar letters refer to similar parts throughout the various views.

Referring to the figures generally, *e* is the ring rail, *d* are the rings, *a* the anti-ballooning members and *i* is the dirt catcher.

The rear of each anti-ballooning member is formed with a radial band or arm *k* by which said members are pairwise jointly secured to eyes *m* formed on to the top of said support and dirt catcher *i*, secured to the ring rail *e* between each two rings *d*.

To permit of concentrically securing said member *a*, it is rendered adjustable on said dirt catcher *i* relatively to the ring by means 55 of a screw or bolt *l* extending through said eyes and a slot *n* in the arm *k*.

The means described, permits also of winding on the cop considerably more yarn than is possible with any other ballooning 60 device, act as a traveler cleaner, and prevent the traveler overrunning when the spindles cease to rotate.

The very close proximity of said annular flat sectioned thread controlling rings to the 65 traveler rings considerably reduces the centrifugal force and consequent friction on the thread as well as between the traveler and the ring and facilitates the thread being wound on the bobbin or cop more evenly, 70 smoother and regular and produces a greater length of thread to be wound on to the bobbin or cop than when the controlling ring is a great distance above away from the traveler ring.

We claim—

1. An anti-ballooning device of the hereinbefore specified type, comprising pairs of annular flat sectional thread controlling rings concentrically located in very close 80 proximity above the traveler rings and having each integrally a rearwardly extending arm, a member located between each pair of said annular rings secured to the ring rail serving both as a support for the said pair 85 of rings and as a dirt catcher and means for individually concentrically securing on said member, said annular rings in relation to the ring on the rail, for the purpose specified.

2. An anti-ballooning device as claimed in 90 claim 1, comprising a support having two eyes, an annular ring having an arm with a radial slot and bolts extending through said slot and the eyes of said member, for the purpose specified.

Signed at Manchester, in the county of Lancaster, England, this 17th day of June, 1920.

FRED FIELDING.
THOMAS POTTER, JUNR.
